DESIGN FOR A TABLE

Pinkus Bandrimer and Joseph Perloff,
Brooklyn, N. Y.

Application September 15, 1938, Serial No. 79,905

Term of patent 3½ years

To all whom it may concern:

Be it known that we, Pinkus Bandrimer and Joseph Perloff, citizens of the United States of America, residing in New York city, in the Borough of Brooklyn, County of Kings, and State of New York, have invented a new, original, and ornamental design for a Table, of which the following is a specification, reference being had to the accompanying drawing, forming part thereof, wherein,

The figure is a front perspective view of a table showing our new design.

We claim:

The ornamental design for a table, substantially as shown.

PINKUS BANDRIMER.
JOSEPH PERLOFF.
